United States Patent Office

Des. 183,447
Patented Sept. 2, 1958

183,447

CHECK STAND

Wayland H. Crawford, San Gabriel, Calif., assignor to Modern Village Stores, Inc., a corporation of California

Application October 10, 1956, Serial No. 43,284

Term of patent 14 years

(Cl. D80—2)

FIG. 1.

FIG. 2.

FIG. 3.

Figure 1 is a top plan view of a check stand showing my new design;

Fig. 2 is a perspective view from one corner of the check stand; and

Fig. 3 is a perspective view from the diagonally opposite corner of the check stand.

The characteristic features of my design reside in the full line portions of the drawing.

I claim:

The ornamental design for a check stand, substantially as shown and described.
